[57] CLAIM

Th ornamental design for a combined automatic pet food dispenser and attached bowl, as shown and described.

DESCRIPTION

FIG. 1 is a perspective view from the front, right side and top of the dispenser of a combined automatic pet food dispenser and attached bowl;

FIG. 2 is a right side elevational view thereof;

FIG. 3 is a rear elevational view thereof;

FIG. 4 is a front elevational view thereof;

FIG. 5 is a left side elevational view thereof;

FIG. 6 is a top plan view thereof; and,

FIG. 7 is a perspective view of a combined automatic pet food dispenser and attached bowl showing my new design, the bowl being symmetrical and the bottom being plain and unornamented.

FIG. 1

FIG. 2

FIG. 3

FIG. 4

FIG. 5

FIG. 6

FIG. 7
